UNITED STATES PATENT OFFICE.

GEORGE W. DOVER, OF CRANSTON, RHODE ISLAND.

SCARF-PIN.

SPECIFICATION forming part of Letters Patent No. 755,856, dated March 29, 1904.

Application filed December 9, 1903. Serial No. 184,387. (No model.)

To all whom it may concern:

Be it known that I, GEORGE W. DOVER, a citizen of the United States, residing at Cranston, in the county of Providence and State of Rhode Island, have invented certain new and useful Improvements in Scarf-Pins, of which the following is a specification, reference being had therein to the accompanying drawings.

My invention relates to scarf and analogous pins primarily designed to prevent accidental displacement by means of a projection upon the pin-stem, and has for its main object neatness and security of the joining means of the pin parts without the use of solder.

I have in a prior patent application, Serial No. 175,064, set forth a solderless structure directed to the above ends which is advantageous for use in plated jewelry, but which is inappropriate for a solid-gold or high grade of goods, besides being weaker and more expensive than my present invention, which is fully described hereinafter in conjunction with the accompanying drawings, wherein—

Figures 1, 2, and 3 show the original pin-stem blank in its successive stages of completion; Fig. 4, a side elevation of the complete scarf-pin, and Fig. 5 a section of the latter on line 5 5 of Fig. 4.

Like reference-letters indicate like parts throughout the views.

My novel structure is formed as follows: The stem is constructed from a blank whose original form is shown in Fig. 1, comprising the longer and shorter cylindrical sections *a* and *b*, respectively, intermediate which are oppositely-directed lateral ears *c*, lying in the same place as the sections. The thickness of the ears is equal or greater than the diameter of the sections *a* *b*. Each ear has perforations *d* at a like distance from their respective margins. The ears *c* are next bent into planes parallel with each other, as shown in Fig. 2, whereby the perforations or openings *d* are brought into alinement with each other. The sections *a* and *b* of the blank are next swaged into pointed cylindrical pin members, the section *b* being inclined rearwardly to form a spur upon the upper extremity of the pin-stem.

It should be observed that in bending the ears, as above described, it is desirable that the bending-points *e* should be slightly distant from the stem portion on either side thereof,

as shown in Fig. 5, by this means insuring a flat surface *i* upon the inner or lower portion of the rectangular socket formed by the bent ears.

The head member *f* of the scarf-pin is provided on its rear face with a rectangular lug *g*, adapted to snugly fit in the socket formed by the bent ears *c* and whose outer face contacts at every point with the flat surface *i*. The lug *g* is traversed by an opening in alinement with the perforations *d* in the ears *c*. Through these three openings is riveted, upset, or frictionally held a dowel-pin *m*.

By the structure above described the head is immovably secured to the pin without solder and in a more secure manner than heretofore employed, and the thickness of the stock comprising the ears obviates the structural weakness prevailing in prior devices of this nature.

Having described my invention, what I claim is—

1. In a scarf-pin the combination with a pin-stem provided with upturned lateral ears, of a head, a lug upon the head provided with a flat extremity resting against the base of the cup formed by the upturned ears, and means for securing rigidly the lug and ears together.

2. In a scarf-pin the combination with a pin-stem provided with upturned lateral ears, of a head, a lug upon the head provided with a flat extremity permanently resting against the base of the cup formed by the upturned ears, and a securing-pin traversing the lug and ears.

3. In a scarf-pin the combination with a pin-stem provided with upturned ears of a thickness approximately the diameter of the pin-stem, of a head, a lug upon the head resting fixedly against the base of the cup formed by the upturned ears, and means for securing the lug and ears.

4. In a scarf-pin, the combination with a pin-stem provided with upturned lateral ears, of a head, a lug upon the head contacting with the base of a cup formed by the upturned ears, and means for rigidly securing the lug and ears together.

In testimony whereof I have affixed my signature in presence of two witnesses.

GEORGE W. DOVER.

Witnesses:

HORATIO E. BELLOWES,
WILLIAM E. BROWN.
